UNITED STATES PATENT OFFICE.

CRAWFORD M. FAIRBANKS, OF LINCOLN, RHODE ISLAND.

MACHINE FOR CUTTING THE EDGES OF FLAT FILES.

SPECIFICATION forming part of Letters Patent No. 374,051, dated November 29, 1887.

Application filed June 6, 1887. Serial No. 240,382. (No model.)

To all whom it may concern:

Be it known that I, CRAWFORD M. FAIRBANKS, of Lincoln, in the State of Rhode Island, have made certain new and useful Improvements in Machines for Cutting the Edges of Flat Files; and I do hereby declare that the following specification, taken in connection with the drawings making a part of the same, is a full, clear, and exact description thereof.

10 Figure 1 is an elevation of my improved machine. Fig. 2 is a transverse section of frame and file-carriage and adjusting devices. Fig. 3 is a transverse section of frame and file-carriage and devices for holding the file. Fig. 4 is a top view of frame and file-carriage and devices for holding the file. Fig. 5 is a modification of the adjusting devices.

15 The object of my invention is to increase the rapidity and facility with which files may be made by machinery and to secure an even wear of the cutting-tool; and it consists in the devices for adjusting the carriage and holding and guiding the file, as hereinafter described.

20 In the drawings, A is the frame of the machine, supported by a suitable standard, B.

25 C is a cutting-tool secured to an arm, D, which is pivoted to the frame and operated by a cam, E, and spring F. The movement of the arm D causes the tool to strike the file-blank 30 secured beneath.

35 G is the file-blank, which is secured upon a carriage, H, diagonally to its line of movement. Motion is communicated to the carriage H by a screw-arbor, I, working through a nut, J, pivoted to the carriage. The file-blank G is placed against a vertical shoulder, K, and held in that position by a spring-actuated rod, L, which accommodates itself to the varying distance of the blank from the side of the carriage.

M is a set-screw working in a horizontal arm, 40 N, and is operated to secure a rocking adjustment of the carriage H.

The placing of the blank diagonally upon the bed secures the even wear of the tool, inasmuch as each portion of its edge will be required to 45 perform a share of the work in passing the length of the blank.

Whenever it is found that the cutting-tool is not striking squarely, but is cutting the teeth deeper upon one side than the other, the operator can easily and quickly make the necessary adjustment of the carriage by raising or depressing (as the case may require) the set-screw M. The spring-actuated rod L operating against the screw will accommodate itself to 55 the new adjustment to hold the carriage at any desired angle or degree of tip.

In Fig. 5 a different construction of the spring-actuated rod is shown, the principle and operation, however, remaining practically 60 the same, the blank being held by a clamp.

What I claim as my invention, and desire to secure by Letters Patent, is—

1. A spring-actuated rod, L, secured to the frame of the machine, in combination with the 65 carriage H, for holding the blank in place, as specified.

2. The combination of the carriage H, the spring-actuated rod L, and the adjusting screw M, for adjusting and holding the carriage at 70 any desired angle, as and for the purposes specified.

CRAWFORD M. FAIRBANKS.
